CONTROL HEAD

Charles E. Beck, Park Ridge, Ill., assignor to
Motorola, Inc., Chicago, Ill., a corporation of
Illinois

Application August 19, 1949, Serial No. 4,613

Term of patent 7 years

(Cl. D26—5)

To all whom it may concern:

Be it known that I, Charles E. Beck, a citizen of the United States, residing in the city of Park Ridge, county of Cook, State of Illinois, have invented a new, original, and ornamental Design for a Control Head, of which the following is a specification, reference being had to the accompanying drawing, forming a part thereof, in which:

Fig. 1 is a perspective view of the front and one end of a control head showing my new design;

Fig. 2 is a plan view of the control head; and

Fig. 3 is an end elevational view of the control head.

I claim:

The ornamental design for a control head, substantially as shown.

CHARLES E. BECK.
